(57) **CLAIM**

The ornamental design for a display panel for automobiles, as shown and described.

DESCRIPTION

1. Display panel for automobiles

1.1 : Front perspective

1.2 : Front

1.3 : Back

1.4 : Left

1.5 : Right

1.6 : Top

1.7 : Bottom

1.8 : Reference view 1

1.9 : Reference view 2

The broken lines depict portions of display panel for automobiles that form no part of the claimed design; reproduction 1.8 is a reference view showing the state of use that the Center Information Display has been rotated at 90 degrees; reproduction 1.9 is a reference view showing the state of use that the claimed design installed at inside of the automobile; this design is a pillar-to-pillar display panel for automobiles comprising of a Cluster Display and a Passenger Information Display which are arranged side by side, and a Center Information Display at the center that provides various information on automobiles; as shown in reproduction 1.8, the Center Information Display can be rotated at 90 degrees clockwise, so it can be used horizontally or vertically depending on the content; when the Center Information Display is used vertically, the hidden area is exposed so that additional content can be seen through the expanded area.

1 Claim, 9 Drawing Sheets
